HENRY C. MILLER, OF WATERFORD, NEW YORK.

STOPPING MECHANISM FOR SEWING-MACHINES.

1,118,790.

Specification of Letters Patent. Patented Nov. 24, 1914.

Application filed February 11, 1905. Serial No. 245,319.

To all whom it may concern:

Be it known that I, HENRY C. MILLER, a citizen of the United States, residing at Waterford, in the county of Saratoga and State of New York, have invented new and useful Improvements in Stopping Mechanism for Sewing-Machines, of which the following is a specification.

This invention relates to improvements in stop mechanism in count stitch sewing machines, used for buttonholing, eyeleting and barring.

In button hole machines, it is essential when the stitching has been completed that the machine be stopped with its needle out of the fabric to facilitate the removal of the same and the insertion of another piece. In devices now used for this purpose, considerable difficulty is experienced in stopping the needle at the proper point, and in some instances starting the needle. Aside from these difficulties with the stopping and starting of the needle at the proper moment, other decided disadvantages exist, due to construction and the incidental operation. In my present improvement, I have sought to cure the defects noted, and have devised a mechanism, which insures of the needle being stopped at the proper time, and binding and consequent holding of the parts are dispensed with.

The prime object of my invention is to provide a stopping mechanism, automatically operated, the stitch forming mechanism running by momentum for a given period when near the end of a button hole, the speed being gradually retarded, until by the time the point of stop is reached, the speed is arrested without jarring or binding of the parts.

I have found by experience with high speed button hole machines, that it is impossible to use a positive stop mechanism, or mechanism of a binding nature to retard the speed. I have therefore provided a construction, which consists essentially of what may be termed a preliminary cushion against which a projection on a revolving part of the operating mechanism strikes, after the power has been cut off, and a final cushioned stopping device to receive the projection as it leaves the preliminary cushion to hold the stitch forming mechanism from further movement. The parts are so located that by the time the preliminary

cushion acts on the power mechanism little or no momentum force remains, and the final stop holds the stitch forming mechanism in a predetermined position. This retarding effect is further accomplished by reason of the fact that the preliminary cushion also acts on the power mechanism after the latter leaves the former, and just at the time the final stopping device is actuated.

Other objects and advantages will be hereinafter referred to and be particularly pointed out in the claims.

In the drawings, Figure 1 is a view in side elevation of a conventional button hole sewing machine, showing my improvement applied thereto. Fig. 2 is an enlarged side elevation of my invention. Fig. 3 is a similar view the parts being shown as moved to impart motion to the stitch forming mechanism. Fig. 4 is an end view, parts being shown in section. Fig. 5 is a diagrammatic view illustrating the position of the parts at the time the power is cut off. Fig. 6 is a similar view showing the position of the parts while the preliminary retarding operation is in progress. Fig. 7 is a similar view showing the position of the parts prior to the engagement of the final stopping device. Fig. 8 is a similar view showing the final stopping device in operation. Fig. 9 is a detail plan view. Fig. 10 is a similar view, the parts being in the position shown in Fig. 8. Fig. 11 is a vertical section of the invention. Fig. 12 is a detail horizontal section of the same on the line 3—3, Fig. 11. Fig. 13 is a view similar to Fig. 11, but showing a slight modification. Fig. 14 is a like view illustrating a further modification. Fig. 15 is a side elevation of the construction shown in Fig. 14.

The numeral 1 indicates a button hole sewing machine, comprising essentially a power shaft 2, with fast and loose pulleys 3 and 4; needle bar 5; holding lever 6; starting bar 7; belt shifting lever 8; stopping lever 9; and automatic means 10 for throwing the stopping mechanism into position. On the starting bar 7 is a coiled spring 12, located between the sewing machine frame and a lug 13 on the bar, and an operating lever 15 engages with a lug 14, the lever 15 being held in proper position by a spring 16.

The general construction of the parts described is well known in the art, and forms no part of the present invention, except in

combination with my improved stopping mechanism.

Secured to the belt shifter lever 8, is an arm 20, having adjustably secured to its free end, belt engaging members 21, adapted to engage the belt 22 to shift it from the fast to the loose pulley, or vice versa. Fast on the power shaft 2 is a heavy balance wheel 23, and adjacent the fast pulley 3 is a disk 24, carrying a projection 25. On a lug extending from the frame 1, the stopping lever 9, is pivoted, and on this lever is a casting 26 having side flanges 27 which form guides for mechanism about to be described. A bar 28 operates between the guides, and its upper end 28^a, is beveled, as shown in Fig. 5, and attached to its lower end is a spring 30, the opposite end of the spring engaging an adjustable screw 31, having a bearing in a lug 32 projecting from the casting 26. A second but considerably stronger spring 33 is secured to the lug 32, and its lower end is formed into a loop which surrounds the lug 29, but normally out of contact therewith. The purpose of this construction is to gradually retard the momentum of the power shaft. When the projection 25 strikes the end of the bar 28, it meets with little resistance, but, as the bar is forced down tension of spring 30 is increased, until the lug 29 contacts with the loop of the enlarged spring, which offers sufficient additional resistance to further, but gradually retard the momentum of the power shaft and the mechanism thereby. As the motion of the power shaft continues, and it resists the tension of the two springs, and to further augment the retarding effect, the projection in its rotation must force itself up the beveled end 28^a, prior to its release from the bar 28. In the revolution of the projection 25, it leaves the bar 28 and the latter immediately flies back under the influence of the springs to normal position, the blow being relieved by a cushion 34. The bar 28 is retained between the guides by a plate 35, as will be readily understood. A pin 36 passes freely through an opening in the bar 28, and it has formed on one end a head 36^a which is normally spaced from the outer edge of said bar, to form a seat 37 which is normally slightly narrower than the diameter of the projection 25. The opposite end of the pin 36 is threaded to receive nuts 38 and a washer 39 and encircling the pin between the washer and the outer wall of the casting 26, is a spring 39^a. The pin and the parts just described in connection therewith, form what I have termed the final cushioned stopping device, and constitutes an important part of the invention. The proportion of the seat 37, relative to the pin 25 has a further function, in that the pin is prevented from engaging the seat should the stopping mechanism be slow in positioning itself in the path of the pin. Under such

circumstances the pin could not engage the seat and would pass it, as shown clearly in Fig. 9.

When starting the sewing machine, the operator pulls down the lever 15, which moves the starting bar 7 outwardly, compressing spring 12, and placing a lug 40 in position for the notched end of the holding lever 6 to engage, to hold the stopping mechanism in set position during the period of forming a button hole. The movement of the bar 7, simultaneously rocks the belt shifting lever 8, and the stopping lever 9, on their pivots, as shown in Fig. 3, which shifts the belt 22 from the loose to the fast pulley, and disengages the projection 25 from its seat 37. Motion having been applied by this operation to the power shaft 2, the stitching of the button hole takes place. The button hole having been completed, the automatic mechanism 10 strikes lever 6, and disengages its end from the lug 40 and the spring 12, throws bar 7 toward the left, which brings the casting 26 and its part against the flange 24, and throws the belt from the fast to the loose pulley, the power shaft, then being run by momentum, the balance wheel 23 assisting. The pivots of the levers 8 and 9 are located with relation to the connection with starting bar 7 so that when the stopping mechanism is to be operated the belt shifter shows the belt from the fast to the loose pulley in advance of the engagement of the pin 25 with the bar 28. This absolutely insures the stopping mechanism overcoming the resistance of the momentum, and not power, as would be the case if the pin engages the stopping mechanism when the belt was on the fast pulley. The stopping mechanism now being in the path of the projection 25, and the latter being propelled by momentum, it first strikes the beveled end 28^a of the bar 28, as shown in Fig. 5, and exerts tension on the preliminary springs 30, and as the movement of the projection progresses, it continues to depress the bar which gradually contacts with the larger spring, and increasing the tension, and consequently retarding the movement of the power shaft, the pin in the meantime rides down the beveled end 28^a, until approximately a line drawn through the center of the shaft is reached as shown in Fig. 6. The momentum of the driving mechanism by this time is well retarded, but to add greater gradual resistance to the travel of the projection 25, the parts are so arranged that during the time said projection travels from the position shown in Fig. 6 to that shown in Fig. 7, it works up the bevel 28^a and as the bar 28 is still being depressed and tension on the springs increased, combined forces are used to gradually reduce the speed. By the time the projection reaches the position shown in

Fig. 7, the momentum of the power shaft is almost lost, but it is essential that it be gradually and firmly stopped at a predetermined point, to properly locate the needle. 5 as hereinbefore pointed out. The head is in the path of travel of the projection 25, and as soon as the latter leaves the top of the bar 28 and travels across the seat 37, it contacts with said head, and immediately the bar 28 10 is returned to its normal position, and in so doing, and while the projection is in the seat 37, the outer edge of the bar contacts with the projection and materially assists in preventing its further rotation. However, 15 this action is incidental, the projection once having reached the seat 37 it contacts with the head, and the spring 39 is of such strength as will effectually receive the final blow of the projection; and while it may 20 yield somewhat, it returns again, together with the projection to normal position, shown in Fig. 8. The parts are so related that when the projection 25 is caught in the seat 37 between the bar 28 and the head, the 25 needle bar is elevated and the operator can quickly proceed to introduce the next article to receive a button hole.

I have found that I can produce a neat, durable, and effective stopping mechanism 30 for a sewing machine, by placing the operative parts so that the projection 25 makes about one third of a revolution by momentum, and during this period retard and eventually stop the stitching mechanism at 35 the desired point, without in any wise jarring or jamming the parts. I also provide and arrange the mechanism with relation to the stopping projection so that in the event the automatic means 10 should disengage 40 the lever 6 from the lug 40, and permit the stopping mechanism striking said projection, the latter will not be broken off. If the stopping mechanism should be slow in being released the projection will ride 45 against the side of the casting and push it away, and then when the pin passes by, said casting under the influence of the spring 12 will be returned to its position in the path of the projection, the latter making a full 50 revolution and then engaging the bar.

In the modification shown in Fig. 13, the mode of connecting the springs 30 and 33 are slightly different; the screw 31^a being at the bottom, and the lug 29^a being at the 55 top.

In Figs. 14 and 15, the final cushioned stopping device is slightly different than that shown in the other figures, but the result obtained is substantially the same. In 60 these figures, 43 indicates a strong flat spring, the upper end being in the path of the pin 25, and forming a head 44, a space being formed between the bar 28 and the head 44 to form a seat 37^a. In the travel 65 of the projection 25, it depresses the bar

28 and gradually leaves the latter and enters the seat 37^a, and is cushioned by the head 44, in substantially the same manner heretofore pointed out.

The construction described produces a 70 stopping mechanism which fulfills all the essential practical requirements to effectually stop the mechanism without undue jar; gradually reduce the high speed of the mechanism to a complete stop in the shortest possible time without disarranging the 75 delicate adjustment of the parts; and stop the mechanism with very little recoil to prevent breaking of the thread.

Another decided important result is accomplished by my improved construction, that is that the parts when operated to stop the mechanism, do not hold the same, as will require a great deal of resistance to disengage the parts when starting the machine. The only resistance to overcome is the disengaging of the projection from its seat, and the tension of the spring on the operating rods, which amounts to very little.

What I claim as new is:

1. In combination, stitch forming mechanism, means operating said mechanism, a projection carried by said operating means, a stopping mechanism coöperating with the operating means, the stopping mechanism comprising a preliminary cushion located in the path of the projection to retard the motion of the operating means, and a final cushioned stopping device located in the path of the projection for stopping the operating means, the preliminary cushion being operated independent of and is spaced from the final cushioned stopping device, the preliminary cushion, and the final stopping device, being operated upon by the projection at different periods, the final cushioned stopping device remaining inoperative until after preliminary stopping device is operated.

2. In combination, stitch forming mechanism, means operating said mechanism, a stopping mechanism coöperating with said operating means, said stopping mechanism comprising a preliminary cushion to retard the motion of the operating means, and including means for automatically returning the preliminary cushion to normal position, and a final cushioned stopping device, the preliminary cushion being independent of the final cushioned stopping device, and adapted to be successively engaged by the means operating the stitch forming mechanism; the final cushioned stopping device remaining inoperative until after the preliminary cushion is operated, the automatic means returning the preliminary cushion to normal position during the period of operation of the final cushioned stopping device.

3. In combination, a stitch forming mech-

- anism, means for operating the same, a projection carried by said means, a stop mechanism comprising a cushioned preliminary retarding bar and a final cushioned stopping bar, the preliminary stopping bar being in the path of travel of the projection when stopping the stitch forming mechanism, means automatically returning the preliminary retarding bar to normal position, the projection frictionally contacting with the preliminary retarder as the latter is returned to normal position and when said projection contacts with the final stopping bar.
4. In combination, stitch forming mechanism, means operating the stitch forming mechanism, a stopping mechanism comprising a preliminary cushion to retard the movement of the stitch forming mechanism, and a final cushioned stopping device, the preliminary cushion and the final cushioned stopping device being mounted independently of each other, whereby each cushion will return to normal position independent of the other, the said cushions being of different resistances, and located in the path of the means operating the stitch forming mechanism, the latter successively engaging the preliminary cushion and the final cushioned stopping device.
5. In combination, stitch forming mechanism, means operating the stitch forming mechanism, stopping mechanism, a preliminary cushion and a final cushioned stop the two cushions being independently operated, and mechanism automatically controlling the movement of the stopping mechanism to throw out the means operating the stitch forming mechanism to bring the preliminary cushion and the final cushioned stop in operative relation with the means operating the stitch forming mechanism to successively and independently engage the same.
6. In combination, stitch forming mechanism, means operating the stitch forming mechanism, stopping mechanism pivoted to move toward and from the means which operates the stitch forming mechanism and comprising a casing, a preliminary cushion and a final cushion stop mounted independent of the other and movable in the casing in different paths, and means operating the stopping mechanism, the preliminary and final cushions being positioned to be engaged by a part of the stitch operating means to be successively engaged thereby.
7. In combination, stitch forming mechanism, means operating the stitch forming mechanism, stopping mechanism comprising a cushioned bar forming a preliminary cushion, and a cushioned final stopping device, the preliminary cushioned bar being at an angle to the final cushioned stopping device and being mounted independently thereof, whereby each cushion will return to normal position independent of the other, and means operating the stopping mechanism, the preliminary cushion and the final cushion being in the path of and successively engaged by a part of the means which operates the stitch forming mechanism.
8. In combination, stitch forming mechanism, means operating the stitch forming mechanism, a stopping mechanism comprising a preliminary retarder, a spring connected to the retarder, and a final cushioned stop spaced from and mounted independently of the preliminary retarder, a spring connected to the final cushioned stop; a part of the means operating the stitch forming mechanism being in the path of the preliminary retarder and the final cushioned stop and adapted to be seated in the space formed between the same.
9. In combination, stitch forming mechanism, means operating the stitch forming mechanism, a stopping mechanism comprising a casing, a slidably mounted preliminary retarder and a slidably mounted final stop mounted in the casing, the final stop being spaced from the preliminary retarder to form a seat, the preliminary retarder, and the final stop being in the path of a part of the mechanism operating the stitch forming mechanism and adapted to be caught in the seat, and means operating the stopping mechanism.
10. In combination, stitch forming mechanism, means for operating the stitch forming mechanism, a projection carried by the operating means, a pivot, stopping mechanism mounted on the pivot and comprising a preliminary cushion and a final cushioned stop spaced from the preliminary cushion, means for mounting the preliminary cushion and the final cushioned stop independently of each other to provide separate paths of movement for said preliminary cushion and final cushion stop and mechanism for rocking the stopping mechanism on its pivot to bring the preliminary cushion and the final cushioned stop into the path of the projection to be successively operated thereby, said projection being caught between and held by the preliminary cushion and the final cushioned stop.
11. In combination, stitch forming mechanism, means operating the stitch forming mechanism, a stopping mechanism comprising a slidably mounted cushioned bar in the path of travel of a part of the means operating the stitch forming mechanism, and means forming with the slidably mounted bar a seat to receive and hold said part of the means operating the stitch forming mechanism, after it leaves the slidably mounted cushioned bar, and means operating the stopping mechanism.
12. In combination, stitch forming mechanism, means operating the stitch forming

- mechanism, a stopping mechanism comprising a slidably mounted cushioned bar in the path of travel of a part of the means operating the stitch forming mechanism and including means for automatically returning said bar to normal position and a slidably mounted cushioned means for holding said part of the means operating the stitch forming mechanism after said part leaves the first mentioned cushioned bar and the latter is returned to normal position and means operating the stopping mechanism. 10
13. In combination, stitch forming mechanism, means operating the same, a stopping mechanism comprising a bar positively connected with a spring, a second and larger spring in the path of but disconnected from the bar, and a final cushioned stop, the bar and the cushioned stop being in the path of a part of the means operating the stitch forming mechanism, the movement of the bar being resisted first by the light spring and gradually picking up the stronger spring, and mechanism operating the stopping mechanism. 15
14. In combination, stitch forming mechanism, means operating the same, a stopping mechanism comprising a spring actuated bar, which is beveled at one end, and a cushioned stop adjacent the bar; the beveled end of the bar being in the path of an engaging part of the means which operates the stitch forming mechanism, the engaging part contacting first with the lower portion of the bevel and gradually moving up to the highest portion where it leaves the bar preparatory to engaging the adjacent cushioned stop, and means operating the stopping mechanism. 20
15. In combination, stitch forming mechanism, means operating the same, a stopping mechanism, comprising a pivoted guide, a bar working in the guide, means connected to the bar for gradually increasing the resistance when the bar is moved, and a cushioned stop spaced from the bar, a projection extending from the means which operate the stitch forming mechanism, the space between the bar and the cushioned stop being of such width that when the projection is therein it will be lightly clamped between the bar and the cushioned stop, and means operating the stopping mechanism. 25
16. In combination, stitch forming mechanism, a power shaft connected to said mechanism, fast and loose pulleys on the power shaft, one of said pulleys having a projection, a belt shifter, a stopping mechanism, coöperating with the projection, said stopping mechanism comprising a pivoted frame having a slidably mounted preliminary retarder and a slidably mounted cushioned stop, the slidably mounted preliminary retarder and slidably mounted cushion
- stop being in the path of the projection and each having separate paths of movement, means connecting the belt shifter and stopping mechanism together, and automatic means for throwing the stopping mechanism into the plane of the projection and the belt from the fast to the loose pulley. 30
17. In combination, stitch forming mechanism, a power shaft connected to said mechanism, a fast and a loose pulley on the shaft, a projection on one of the pulleys, a belt shifter, a pivoted stopping mechanism which comprises a slidably mounted preliminary retarder and a slidably mounted final cushioned stop, the stopping mechanism being pivoted at a point if the projection should prematurely pass the end of the preliminary retarder the stopping mechanism will be held out of the path of said projection means connecting the stopping mechanism and the belt shifter, means for automatically throwing the stopping mechanism toward the projection and the belt from the fast to the loose pulley. 35
18. In combination, stitch forming mechanism, a stopping mechanism comprising a frame in which is mounted a cushioned preliminary retarder, and a final cushioned stop independent of and spaced from the preliminary retarder and mounted independently thereof, whereby the retarder and the cushioned stop will return to normal position independent of the other, the preliminary retarder and the final stop each having a different path of movement in the frame, and means coöperating with the stopping mechanism for stopping the stitch forming mechanism at a predetermined point. 40
19. In combination, stitch forming mechanism, means operating the same, a stopping mechanism comprising a slideable preliminary retarding bar, and a slideable final cushioned stop, mounted independent of the preliminary movable retarding bar means 105 operating the stopping mechanism to bring the preliminary retarding bar and the final cushioned stop in the path of travel of a part of the means operating the stitch forming mechanism, said part being retarded 110 by contact with the preliminary retarding bar as the latter returns to normal position and the part engages the final stop. 115
20. In combination, stitch forming mechanism, power mechanism having a projection which has a predetermined path of travel, stopping mechanism comprising a preliminary retarder composed of a series of retarding means mounted to move in independent paths and successively operated 120 by the projection, and an independent stop located in the path of travel and engaged by the projection, said projection being held between the preliminary retarder and the final stop when its movement is arrested. 125

21. In combination, stitch forming mechanism, power mechanism carrying a projection, means communicating power to the power mechanism, a movable stop mechanism including a preliminary cushioned retarder and a final cushioned stop mounted to move independent of the movement of the preliminary cushioned retarder, said movable stop mechanism co-operating with the projection to stop the stitch forming mechanism, means automatically moving the stop mechanism into the path of the projection, a spring normally holding the stop mechanism in the path of the projection, the stop mechanism being positioned relative to the projection whereby if said stop mechanism be moved for operation after the projection is past the engaging point, said projection will act on the stop mechanism and hold it out of its path, the spring moving the stop mechanism to operative position after the projection passes. 70
22. In combination, stitch forming mechanism, means operating the same which is provided with a projection adapted to travel in a predetermined path, stopping mechanism comprising a preliminary cushioned bar, and a final cushioned stop independent of the preliminary cushioned bar, the preliminary cushioned bar and final cushioned stop being in the path of the projection and operable in different paths when the stopping mechanism is operated. 75
23. In combination, stitch forming mechanism, means operating the same which is provided with a projection adapted to travel in a predetermined path, stopping mechanism comprising a preliminary cushioned bar, a cushioned final stop spaced from the preliminary cushioned stop, said space being normally narrower than the projection, the latter forcing the final stop away from the preliminary retarder and widening the space to receive the projection, and means operating the stopping mechanism to bring the preliminary and final cushions into the path of the projection. 80
24. In combination, stitch forming mechanism, means for operating the same, a projection on said operating means, preliminary cushioned bar forming a retarder, a final cushioned stopping bar, and means bringing the preliminary cushioned bar and the final stopping bar into position where the projection will contact with the ends of said bars to first retard the movement of the operating means and finally stop said movement. 85
25. In combination, stitch forming mechanism, means for operating the same, a projection on said operating means, stopping mechanism comprising a preliminary cushioned bar forming a retarder, the engaging end of the bar being beveled, a final cushioned stopping bar, and means moving the stopping mechanism toward the projection to cause the latter to contact with the beveled end and press the preliminary bar past the final stopping bar and then engage the latter. 90
26. In combination, stitch forming mechanism, means for operating the same, a projection on said means, a stop mechanism comprising a casing in which is mounted a preliminary retarder and a final stop, a pivot on which the stop mechanism is mounted, the preliminary retarder and final stop being slidably mounted in the casing, means for locking the stop mechanism out of operative position, and means for throwing the stop motion in the path of the projection. 95
27. In combination, a sewing mechanism, power mechanism having a projection traveling in a predetermined path, hinged stopping mechanism adapted to be moved toward and from the path of the projection including a preliminary and a final stop, means for locking the stopping mechanism out of operation, automatic means for releasing the stopping mechanism, and means permitting of the projection acting on the stopping mechanism to hold the latter out of the path of said projection when said stopping mechanism is slow in being released to permit the projection to pass the final stop, said means also positioning the stopping mechanism in the path of the projection to contact therewith in its next movement. 100
28. In combination, stitch forming mechanism, a power shaft, power operating means on the power shaft, a pivoted stop mechanism comprising a casing in which is mounted a preliminary retarder and a final stop, the preliminary retarder and the final stop being mounted independent of each other in the casing, and operated independently of the other in separate paths of movement, means for starting the power shaft, means connecting the latter means and the stop mechanism, means for locking the stop mechanism out of operative position, and means for throwing the stopping mechanism into operative position to stop the stitch forming mechanism and simultaneously shift the means which starts the shaft. 105
29. In combination, stitch forming mechanism, power mechanism having a co-operative stop element, a casing in which is mounted a movable preliminary retarder and a movable cushioned final stop mounted independent of and spaced from the preliminary retarder, the space forming a seat in which the co-operative stop element is caught after operating the preliminary retarder. 110
30. In combination, stitch forming mechanism, means for operating the same, a projection carried by said means, a stop mechanism comprising a cushioned preliminary 115

retarding bar and a final cushioned stopping bar, the preliminary bar and the final stopping bar being in the path of travel of the projection when stopping the stitch forming mechanism, means automatically returning the preliminary bar to normal position when the projection contacts with the final stopping bar.

31. In combination, stitch forming mechanism, means for operating the same, said means having a projection, a preliminary retarder which is beveled at the point where the projection contacts with it, a final cushioned stop, and means permitting a relative movement between the final stop and the preliminary retarder to cause the projection to contact with said preliminary retarder and the final cushioned stop when the projection is being arrested.

32. In combination, stitch forming mechanism, means for operating the same, said means having a projection which travels in a circle, a preliminary retarder which is beveled at the point where the projection contacts with it, the highest point of the bevel being nearest the center of the circular path of travel of the projection, a final cushioned stop, and means permitting a relative movement in the final stop and the preliminary retarder for moving the projection to contact with said preliminary retarder and the final cushioned stop when the projection is being arrested.

33. In combination, stitch forming mechanism, power mechanism having a projection which travels in a predetermined path, stopping mechanism comprising a frame carrying a preliminary retarder, and a final cushioned stop mounted independently of the preliminary retarder, the projection when arrested being held between and in contact with the preliminary retarder and the final stop.

34. In combination, stitch forming mechanism, means for operating the same including a rotary shaft and a fast pulley and a loose pulley, a projection on the fast pulley, a belt shifter, holding means for retaining said belt shifter in position so that the driving belt will run on said fast pulley, automatic means for tripping said holding means and for moving said belt shifter to transfer the driving belt from said fast to loose pulley, a movable positive stopping device for said shaft, and a retarding device operable in a different path of movement than the positive stopping device and which is operated independently of said positive stopping device and which is released when the said belt shifter is removed to transfer the said driving belt to said loose pulley, the said retarding device being so arranged that when thus released it will be forced in the path of movement of the projection on the fast pulley to arrest or retard the rota-

tion thereof before the said positive stopping devices comes into operation, so as to soften the jar or shock of the final stop.

35. In combination, stitch forming mechanism, means for operating the same including a rotary shaft and a fast pulley and a loose pulley, a swinging frame, an arresting or retarding device for said shaft, mounted in the swinging frame, a positive stopping device, mounted in the swinging frame and arranged to move in a path transverse with respect to the arresting or retarding device, and means for tripping the swinging frame to position the arresting or retarding device and the final stopping device to first retard the movement of the rotary shaft and subsequently stop said shaft at a determinate point, and means for causing the arresting or retarding device to assume its normal position before the shaft is finally stopped.

36. In combination, stitch forming mechanism, means operating the same including a rotary shaft and a fast pulley and a loose pulley, a positive stopping device, a retarding device mounted independently of the positive stopping device and including a projection and a cushioned stop therefor, a belt shifter operatively connected with the retarding device, means for shifting the belt shifter to throw the belt from the fast to the loose pulley before the cushioned stop of the retarding device contacts with its projection, the positive stopping device being located to operate after the retarding device is operated.

37. In combination, stitch forming mechanism, means operating the same including a rotary shaft and a fast and loose pulley, a belt shifter, a retarding device operatively connected with the belt shifter, the connection moving the belt in advance of the movement of the retarding device, a positive stopping device mounted independently of the retarding device to finally stop the shaft at a determinate point after operation of the retarding device, and means for operating the belt shifter to move the belt from the fast to the loose pulley and the retarding device, the belt at all times engaging the loose pulley previous to operation of the retarding device.

38. In combination, stitch forming mechanism, including a drive shaft and a lug revolving therewith a swinging frame adapted to move in a path longitudinal with respect to the axis of said shaft, a spring plunger carried by said frame, said plunger arranged to move longitudinally in said frame in a direction toward and away from said shaft, a second spring plunger carried by said frame and arranged to move therein in a path transverse with respect to the first said plunger, means for holding said frame in a position whereby the two plungers will clear

the lug, and means for tripping the frame to bring the lug in line with the plungers and also disconnect the drive shaft from its driving mechanism.

- 5 39. In combination, stitch forming mechanism, including a drive shaft, a swinging frame and two spring pressed plungers mounted therein and carried thereby, one of said plungers constituting an arresting or
10 retarding device for the driving shaft, and the other a positive stop, which yields within certain limits, a lug revolving with the drive shaft and adapted to engage both said

plungers, means for moving the swinging frame to bring said plungers into and out of 15 line with the lug, and means carried by said frame for disengaging the shaft from its driving mechanism.

In testimony whereof I affix my signature, in presence of two subscribing witnesses. 20

HENRY C. MILLER.
